UNITED STATES PATENT OFFICE.

STACY B. HASELTINE, OF CHICAGO, ILLINOIS, ASSIGNOR, BY MESNE ASSIGNMENTS, TO
W. H. MINER, INC., A CORPORATION OF DELAWARE.

SHOCK-ABSORBING MECHANISM.

Application filed April 19, 1923. Serial No. 633,048.

This invention relates to improvements in shock absorbing mechanisms.

One object of the invention is to provide a shock absorbing mechanism of simple, efficient, strong and durable construction, composed of few parts and capable of being cheaply manufactured, wherein a plurality of longitudinally arranged, intercalated plates serve as follower-acting elements.

A further object of the invention is to provide a mechanism of the character indicated, in which the cushioning means are enclosed within recesses formed in the plates and housed entirely within said plates.

A still further object of the invention is to provide a tandem spring shock absorbing mechanism, in which both springs will be compressed under both draft and buffing strains, and in which the customary intermediate stops or shoulders on the side plates or stop castings may be dispensed with, as well as the customary intermediate abutment block on the drawbar yoke.

Another and more specific object of the invention is to provide a tandem spring shock absorbing mechanism of the character indicated, wherein a plurality of longitudinally arranged, intercalated plates, each provided with a pair of elongated openings, serve as the follower acting elements, the plates being arranged in two sets, one set co-acting in normal position with the rear end of the draw bar and the other with the rear end of the yoke.

Other objects and advantages of the invention will more clearly appear from the description and claims hereinafter following.

In the drawing forming a part of this specification, Fig. 1 is a longitudinal sectional view of a portion of a railway draft rigging, taken along the inner side of one of the draft sills, showing my improvements in connection therewith. Fig. 2 is a vertical, transverse, sectional view corresponding substantially to the line 2-2 of Fig. 1. And Fig. 3 is a plan view of one of the follower-acting plates.

In said drawing, 10-10 denote channel shape center or draft sills of a car under-frame, each of said draft sills having a front stop lug 11 and a rear stop lug 12 secured to the inner face thereof. A por-

tion of the drawbar is indicated at 13, and the same is operatively connected to an ordinary single pocket yoke indicated at 14, by means of a transversely arranged key 15 extending through the draft sills and working in aligned slots therein, one of said slots being indicated in dotted lines in Fig. 1. The shock absorbing mechanism proper is contained within the yoke 14 and all the parts are supported by a saddle plate indicated at 15'.

The improved shock absorbing mechanism proper, as shown, comprises, broadly, a plurality of follower-acting plates A, B, C, D, E and tandem arranged springs F-F'.

The plates A, B, C, D and E are of rectangular shape and of equal length. The plates A, C and E are alternated with the plates B and D, the plates A and E being arranged outermost and the plate C being interposed between the plates B and D. As clearly shown in Fig. 1, the rear ends of the plates A, C and E abut the inner face 16 of the rear wall of the yoke and are adapted to coact with the rear stop lugs 12 in a well known manner. The front ends of the plates A, C and E are arranged in spaced relation to the front lugs 11, the plates being shorter than the distance between the rear and front lugs an amount corresponding to the permissible stroke of the mechanism. The front end of the plates B and D normally abut the front lugs 11 and the rear end of the drawbar. In Fig. 1 of the drawing, the plates A, B, C, D and E are shown in the position assumed when the gear is in full release.

The plates A and E are of like construction, preferably being exact duplicates, the same being arranged merely in reverse positions with reference to each other. Each of the plates A and E is provided with a pair of longitudinally arranged, spaced, concave recesses 18 and 19, extending partly through the same, each of said recesses being provided with front and rear, flat, abutment walls 20 and 21. The concavity of the recesses 18 and 19 corresponds in curvature approximately to the curvature of the springs F and F'. As clearly shown in the drawings, the recesses 18 and 19 are of equal length and the front and rear end walls 20 and 21 of each recess are adapted to coact at the opposite ends of one of the

tandem arranged springs F and F'. Between the recesses 18 and 19, and at its opposite ends, each plate A and E has the inner face thereof provided with a longitudinally arranged rib 23, having a flat horizontal face and converging side faces. The ribs 23 project toward the axis of the gear and are adapted to engage within correspondingly shaped slots 24 in the abutting faces of the adjacent plates B and D. The ribs have their end faces in alinement with the walls 20 and 21 of the recesses 18 and 19, so as to form continuations of said walls, thereby providing abutment portions, for a purpose hereinafter described.

The plates B and D are of like construction, preferably being exact duplicates, and are arranged in reverse position. Each of the plates B and D is provided with a pair of longitudinally arranged, spaced apart openings 25 and 26. Each opening 25 and 26 is provided with flat, front and rear, end walls 27 and 28 and longitudinally extending side walls curved on the same radius as the concave walls of the recesses 18 and 19. The front and rear end walls 27 and 28 are spaced apart a distance equal to the spacing between the walls 20 and 21 of the respective recesses 18 and 19, and are adapted to aline therewith when the plates are in the position shown in Fig. 1.

The plate C is also provided with longitudinally arranged, spaced openings 29 and 30, each having a flat, front end wall 31, a flat, rear end wall 32, and longitudinally extending side walls curved transversely on a radius corresponding to the radius of curvature of the side walls of the openings 25 and 26 of the plates B and D and the curvature of the convex walls of the recesses 18 and 19 of the plates A and E. The front and rear end walls 31 and 32 of the openings 29 and 30 are also spaced apart a distance equal to the spacing of the front and rear walls of the openings in the plates B and D and the walls of the recesses in the plates A and E, and are adapted to form abutments for the opposite ends of the tandem arranged springs.

As clearly shown in Fig. 1, the front and rear walls of the openings 18, 25 and 29 and the front and rear walls of the openings 19, 26 and 30 of the plates are in alinement when the gear is in released position, thereby defining a front spring chamber G and a rear spring chamber H respectively, adapted to receive and house the springs F and F'.

The springs F and F' each consist of an outer relatively heavy coil and an inner relatively lighter coil. In this connection it will be noted that the ribs 23 on the plates A and E extend inwardly toward the axis of the gear a sufficient distance to overlap the outer portions of the inner coils F and F', whereby the transverse, vertical abut-

ment faces of said ribs are adapted to engage with the opposite ends of said coils as clearly shown in Figs. 1 and 2.

The operation of the improved shock absorbing mechanism is as follows, assuming a buffing action of the mechanism. Upon rearward movement of the yoke 14, the plates B and D will be moved rearwardly by engagement with the butt of the draw-bar, sliding relatively to the plates A, C and E which are held in fixed position by engagement of the rear ends thereof with the rear stop lugs 12. Upon rearward movement of the plates B and D, the front abutment walls 27 of the front and rear recesses thereof will approach the rear walls 21 and 32 of the plates A, E and C, thereby compressing the springs F and F'. This rearward movement of the plates will continue until the rear ends of the plates B and D engage the stop lugs 12, whereupon the pressure will be transmitted directly through the plates A, B, C, D and E, the parts being so proportioned that the mechanism will be solid before the springs are completely compressed, thereby preventing the springs from being driven solid.

Upon the actuating pressure being relieved the springs F and F' will act to restore the parts to normal position, again bringing the front and rear end walls of the recesses into alinement.

During draft, the action is the reverse of that just described, the plates A, C and E being moved forwardly relatively to the plates B and D, which are held in fixed position by engagement with the front stop lugs 11.

It will be evident that the plates A, B, C, D and E may be very cheaply manufactured in the form of forgings or castings, and that the entire construction is exceedingly simple, especially as only three different constructions of plates are required, the plates B and D being duplicates and the plates A and E also being duplicates.

It will also be evident that an exceedingly rigid abutment is provided by the plates when the mechanism is solid, the plates forming in effect a solid column or block, the only open space therein being that occupied by the springs.

Although I have herein shown what I now consider the preferred manner of carrying out the invention, the same is merely illustrative and I contemplate all changes and modifications that come within the scope of the claims appended hereto.

I claim:

1. In a shock absorbing mechanism, the combination with a plurality of pressure-transmitting elements having recesses therein, said elements being of equal length and alternated, and the front and rear ends of adjacent elements being staggered; of cush-

ioning means enclosed within said recesses and opposing relative movement of said elements.

2. In a spring shock absorbing mechanism, the combination with front and rear abutment means; of a plurality of longitudinally arranged intercalated pressure transmitting elements, all of said elements having the extreme end faces thereof co-operating with said front and rear abutment means, said elements also having limited movement relative to said abutment means, the front and rear ends of said elements being arranged in staggered relation with the front ends of alternate elements projecting forwardly of the adjacent elements, and with the rear ends of the latter elements projecting rearwardly beyond the rear ends of the first named alternate elements when the mechanism is in full release; and spring resistance means opposing relative movement of said elements.

3. In a spring shock absorbing mechanism, the combination with a plurality of longitudinally arranged, intercalated, pressure-transmitting elements, each provided with a plurality of spring receiving recesses; the end walls of the respective recesses of each plate being normally in transverse alignment with the end walls of the respective recesses of the remaining plates; of means for moving all of said plates relatively to each other for effecting relative displacement of said aligned end walls; and spring resistance means enclosed within said recesses and co-acting with the opposite end walls thereof.

4. In a tandem gear, the combination with a plurality of pressure-transmitting elements, each provided with a pair of openings therein, said elements being alternated and arranged with the opposed end walls of the pairs of openings of each element in alignment with the opposed end walls of the pairs of openings in the remaining elements, said pairs of openings being in registration; of tandem arranged cushioning means within said openings co-acting with the end walls thereof; and means for moving all of said elements relatively to each other.

5. In a tandem gear, the combination with front and rear abutment means; of a plurality of longitudinally arranged intercalated pressure transmitting elements, each element having the front and rear ends thereof co-operating respectively with said front and rear abutment means to limit the longitudinal movement of said elements, adjacent elements having their front and rear ends arranged in staggered relation when said gear is in full release position; and tandem arranged springs opposing relative movement of said elements.

6. In a tandem gear, the combination with a plurality of longitudinally arranged, intercalated, pressure-transmitting elements,

each of said elements being provided with front, rear and intermediate abutment shoulders to form spring-receiving chambers, corresponding shoulders of said plates being in alinement; of a spring resistance interposed in the chamber between the front and intermediate abutment shoulders; a second spring resistance interposed in the chamber between said intermediate and rear abutment shoulders; means for moving said plates relatively to each other; and front stop means for maintaining certain of said elements stationary during draft and rear stop means for maintaining the remaining elements stationary during buff.

7. In a tandem gear, the combination with a plurality of intercalated pressure transmitting plates, alternate plates having their front and rear ends aligned and adjacent plates having their front and rear ends staggered when the gear is in full release position; of a tandem arranged spring resistance opposing relative movement of said plates; and front and rear stops co-operating with the opposite ends of each of said plates to limit the longitudinal movement thereof.

8. In a tandem gear, the combination with a drawbar, a yoke and front and rear abutments; of a plurality of longitudinally arranged relatively movable pressure transmitting elements, the front ends of said elements being normally alternately in abutment with and spaced from the front abutments and the inner transverse face of the rear end of the drawbar, the elements having their front ends spaced from said front abutments being adapted to have their movement limited by engagement with said abutments upon full compression of the mechanism during draft, and the rear ends of said elements being normally alternately in abutment with and spaced from the rear abutments and the inner side of the rear end of said yoke, the elements having their rear ends spaced from said rear abutments being adapted to have their movement limited by engagement with said abutments upon full compression of the mechanism during buff; and tandem arranged springs adapted to oppose relative movement of said elements.

9. In a tandem gear, the combination with a drawbar, a yoke, and front and rear abutments; of a group of longitudinally arranged, relatively movable pressure transmitting elements, alternate elements of said group having the front and rear ends thereof respectively spaced from the front abutments and in abutment with the rear abutments, and the remaining elements having the front and rear ends thereof respectively in abutment with the front abutments and spaced from the rear abutments, said front ends and said rear ends of all of said plates being adapted to be brought respectively into

alinement when the mechanism is fully compressed with the normally spaced ends thereof in abutment with the respective abutments, said elements being each provided with a pair of spring receiving recesses; and tandem arranged springs housed in said recesses and adapted to oppose relative movement of said elements.

10. In a tandem gear, the combination with a drawbar, a yoke, and front and rear abutments; of a plurality of longitudinally arranged, relatively movable, pressure-transmitting elements, said relatively movable elements having the front ends thereof alternately in abutment with and spaced from the front abutments and the innermost side of the rear end of the drawbar, and the rear ends thereof alternately in abutment with and spaced from the rear abutments and the inner side of the rear end of said yoke; and tandem arranged springs adapted to oppose relative movement of said elements, said yoke and elements being so proportioned and arranged that the opposite ends 23 of all of said elements will simultaneously abut one of said sets of abutments and one end of said yoke or rear end of said drawbar, when the gear is fully compressed, whereby said plates act as a solid abutment 30 and prevent the springs from being driven solid.

11. In a spring shock absorbing mechanism, the combination with front and rear abutment stops; of a plurality of longitudinally arranged, intercalated, pressure-transmitting elements, having the front and rear ends thereof arranged in staggered relation; of a cushioning means opposing relative movement of said elements; and

means for effecting relative movement of 40 said elements to bring their front ends and rear ends respectively in alinement, thereby providing a solid column load-sustaining member when the mechanism is fully compressed to prevent the cushioning means 45 from being driven solid.

12. In a shock absorbing mechanism, the combination with front and rear stop means; of relatively movable longitudinally disposed pressure transmitting members, each of said members having front and rear and front intermediate and rear intermediate spring follower acting means thereon, the corresponding spring follower acting means of said members being relatively displaceable during relative movement of said members; abutment means at the opposite ends of each of said members adapted to co-operate with the front and rear stop means; tandem arranged springs resisting relative 60 movement of said members; and means for effecting relative movement of said members.

13. In a shock absorbing mechanism, the combination with front and rear stops; of relatively movable pressure-transmitting members each having abutment means at the front and rear ends thereof adapted to co-operate with said front and rear stops respectively, each member also having front and rear spring follower acting abutments 70 thereon; spring means for resisting movement of said members; and means for effecting relative movement of said members.

In witness that I claim the foregoing I have hereunto subscribed my name this 17th 75 day of April, 1923.

STACY B. HASELTINE.
